UNITED STATES PATENT OFFICE

155,417

DESIGN FOR A HIGHWAY REFLECTOR
SIGNAL

Ralph R. Gunderson, Chicago, Ill.

Application June 24, 1948, Serial No. 147,170

Term of patent 14 years

(Cl. D72—1)

To all whom it may concern:

Be it known that I, Ralph R. Gunderson, a citizen of the United States, residing at Chicago, county of Cook, and State of Illinois, have invented a new, original, and ornamental Design for a Highway Reflector Signal, of which the following is a specification, reference being had to the accompanying drawing, forming a part thereof, in which:

Figure 1 is a front elevational view of a highway reflector signal, showing my new design; Fig. 2 is a side elevational view thereof; and Fig. 3 is a top plan view.

I claim:

The ornamental design for a highway reflector signal, as shown.

RALPH R. GUNDERSON.
